UNITED STATES PATENT OFFICE.

ALBERT NIOLA AND MICHAEL MARINO, OF NEWARK, NEW JERSEY.

DESIGN FOR A FINGER RING.

Application filed May 21, 1923. Serial No. 6,236. Term of patent 7 years.

To all whom it may concern:

Be it known that we, ALBERT NIOLA and MICHAEL MARINO, citizens of the United States, residing in the city of Newark, county of Essex, and State of New Jersey, have invented a new, original, and ornamental Design for Finger Rings, set forth in the following specification, reference being had to the accompanying drawing, forming a part hereof, wherein—

Fig. 1 is an edge view of a finger ring with the design impressed thereon.

Fig. 2 is a side view of a ring, showing the design upon both sides of the setting.

We claim:—

The ornamental design for a finger ring, substantially as shown.

ALBERT NIOLA.
MICHAEL MARINO.
